No. 823,953.

PATENTED JUNE 19, 1906.

J. F. MEIGS & E. A. GATHMANN.

PROJECTILE.

APPLICATION FILED JULY 28, 1905.

UNITED STATES PATENT OFFICE.

JOHN F. MEIGS AND EMIL A. GATHMANN, OF SOUTH BETHLEHEM, PENNSYLVANIA, ASSIGNORS TO BETHLEHEM STEEL COMPANY, OF SOUTH BETHLEHEM, PENNSYLVANIA, A CORPORATION OF PENNSYLVANIA.

PROJECTILE.

No. 823,953.

Specification of Letters Patent.

Patented June 19, 1906.

Application filed July 28, 1905. Serial No. 271,611.

To all whom it may concern:

Be it known that we, JOHN F. MEIGS and EMIL A. GATHMANN, citizens of the United States, and residents of South Bethlehem, 5 Northampton county, State of Pennsylvania, have invented certain new and useful Improvements in Projectiles, of which the following is a specification.

The present invention comprises various 10 improvements in projectiles, and particularly in explosive projectiles.

The objects of the invention are to provide 15 a tracer for the projectile by means of which its course may be observed, to provide an improved gas-check, and to reinforce the fuse and prevent the same from being blown out by the explosion of the contents of the shell.

The invention will be described in connection 20 with the accompanying drawings, in which—

Figure 1 is a sectional view of a shell embodying the invention, and Figs. 2, 3, and 4 are partial sectional views showing other embodiments of the invention.

Referring to Fig. 1 of the drawings, A indicates an explosive projectile having a longitudinal cavity 1 for the explosive material. The design and dimensions of the shell form no part of the present invention, and they 25 may be varied as desired. Centrally arranged in the rear end of the shell is a fuse 2. A centrifugal percussive fuse is illustrated; but the present invention is not limited to any particular style or kind of fuse. The

30 fuse 2 is screwed into an axially-threaded opening in the rear of the shell. In order to connect the fuse securely to the shell and to provide for the tracer attachment hereinafter described, an integral boss or rearward projection 3 is provided on the rear end of the shell. This boss is threaded internally to receive the fuse, and it is threaded externally to receive the combined strengthener, gas-check, and tracer device B. As shown in 35 Fig. 1, the strengthener, gas-check, and tracer device B consists of a hollow cap 4, having an internally-threaded recess by means of which it is fitted over and screwed tightly onto the boss 3. The base 5 of the recess is arranged to fit against the base 6 of the fuse, and the forward annular portion of the device B, surrounding the recess, fits tightly

against the rear shoulder 7 of the projectile. The device B therefore forms a support for, the fuse and a gas-check to prevent the gases of the firing charge from injuring or passing 55 the fuse. The tracer device B is in the form of a hollow cap having a relatively large chamber 8, in which is stored material adapted to be discharged during the flight of the 60 shell to indicate its path to the eye. This material may be of a pyrotechnic nature to produce a light at night, or it may be a dark fluid or semifluid or powder visible in the daytime when discharged during the flight of the 65 projectile. As shown, the chamber 8 is provided with one or more outlets 9 in its circumference, through which material, if fluid or comminuted, will be driven by centrifugal force during the flight of the shell. The 70 chamber 8 is also provided with a filling-opening closed by plug 10. A small opening 11 is provided in the plug to permit of the entrance of air in order to facilitate the discharge of the contents from the opening or 75 openings 9. This air-inlet is not strictly essential, however. The opening 11 also serves to ignite the contents of the tracer device B when a pyrotechnic compound is used, in which case the burning gases will be ejected 80 from the opening 11.

In Fig. 2 we have shown a form B' of tracer device which differs from the form B only in the location of the filling-opening, which in this instance is in the inner wall of the chamber 8 and is closed by a plug 12.

In Fig. 3 is shown a form of the device in which there is an annular chamber 13 for the tracer material, a recess 14 being formed in the outer central portion opposite the recess 90 which receives the boss 3, these two recesses being separated by a wall 15, which rests upon the base 6 of the fuse. This form of the tracer device is stronger and better adapted to withstand the pressure of gases in the gun. 95 In using any of the forms of the tracer device the material should be packed solidly in the chamber to prevent collapse under the pressure of the gases in the gun.

Fig. 4 illustrates a form of device having a circular cavity 16 in its outer portion and an annular cavity 17 surrounding the boss 3, the cavities being connected by openings in the partition-wall 18. In the forms of the

tracer device shown in Figs. 3 and 4 the chambers or cavities are filled through an annular opening 19, which is afterward closed by the rear end of the projectile.

5 It will be seen that the various forms of projectiles now in common use may be adapted with very slight alterations to receive the gas-check and tracer device herein described. It is only necessary that the shell shall have a 10 boss or projection threaded or adapted to receive the casing of the tracer device and that the latter device shall be made to conform closely to the base of the shell to prevent the passage of gases to the inside of the projectile.

15 Having described our invention, what we claim as new, and desire to secure by Letters Patent, is—

1. The combination with a projectile having a rearwardly-extending boss, of a tracer device having a chamber for tracer material, and means for securing said tracer device to said boss.

2. The combination with a projectile having a rearwardly-extending boss, of a fuse seated in said boss, and a tracer device having a threaded engagement with the boss and being fitted to the rear shoulder of the projectile to form a gas-check.

3. The combination with a projectile having a fuse centrally arranged in its rear end,

of a tracer device having a threaded engagement with the rear end of the projectile and having a wall extending across the rear of the fuse, said casing having an opening for the discharge of tracer material and serving as a 35 gas-check and reinforce for the fuse.

4. The combination with a projectile having a rearwardly-extending threaded boss, of a tracer device comprising a hollow casing having a threaded recess engaging said boss. 40

5. The combination with a projectile having its rear end externally threaded and having a fuse seated in said rear end, of an internally-threaded device engaging the external thread of the projectile and extending over 45 and forming a gas-check for the fuse.

6. The combination with a projectile having at its rear end a rearwardly-extending externally-threaded boss, and having a fuse seated in an opening in said boss, of an internally-threaded device engaging said threaded boss and forming a gas-check for the fuse.

In testimony whereof we have signed our names to this specification in the presence of two subscribing witnesses.
